UNITED STATES PATENT OFFICE.

FREDERICK D. RAMEAU, OF SEATTLE, WASHINGTON.

DAYLIGHT PLATE-DEVELOPING TRAY.

1,195,498.

Specification of Letters Patent.

Patented Aug. 22, 1916.

Application filed September 28, 1914. Serial No. 863,958.

To all whom it may concern:

Be it known that I, FREDERICK D. RAMEAU, a citizen of the United States, residing at Seattle, in the county of King, State 5 of Washington, have invented certain new and useful Improvements in Daylight Plate-Developing Trays; and I do hereby declare the following to be a full, clear, and exact description of the invention, such as will 10 enable others skilled in the art to which it appertains to make and use the same.

This invention relates to photographic apparatus, particularly to devices for developing photographic plates, and has for 15 its object the provision of a novel and efficient device whereby photographic plates may be transferred directly from the ordinary plate holder into a developing tray, the entire operation being accomplished in 20 broad daylight without danger of exposure of the plate.

An important object is the provision of a device of this character having means whereby the spring pressed bar holding 25 the plates in the holder may be moved for releasing the plate so that it may be deposited within the tray.

Another object is the provision of a device of this character having means whereby 30 the plate holder containing the plate or plates to be developed may be securely clamped in relation to the tray.

Another object is the provision of a device of this character which will be simple 35 and inexpensive in manufacture, efficient and durable in service, and a general improvement of the art.

With these and other objects and advantages in view, the invention consists in the 40 novel construction and arrangement of parts as will be hereinafter more fully described and claimed and illustrated in the accompanying drawing, in which—

Figure 1 is a side elevation of the device 45 complete showing a plate holder in position, Fig. 2 is a top plan view, Fig. 3 is a longitudinal sectional view, Fig. 4 is a similar view showing the spring pressed bar of a plate holder pulled back, and Fig. 5 is a 50 perspective view of the tray engaging frame.

Referring more particularly to the drawing the numeral 10 designates a tray such as is commonly employed in the developing of photographic plates. One end of the tray is 55 provided with a tube 11, curved as shown and provided with a funnel 12 extending up-

wardly therefrom adjacent the highest portion of the curve. Disposed upon the top of the tray 10 is a block or plate 13, rectangular in shape and provided with an opening 14 60 slightly larger than the plates to be developed. Disposed above the block 13 is a block or plate 15 provided at one end with a rib 16 extending downwardly from its under face. The block 15 is connected with 35 the block 13 by a plurality of leaf-springs 17 secured upon the block 13 as shown at 18 and secured to the block 15 as shown at 19. These springs urge the block 15 downwardly in relation to the block 13.

In the use of the device, a plate holder of the ordinary type comprising a frame 20, partition 21, slides 22 and the spring pressed bars 23 retaining the plates 24 in position, is inserted between the blocks 13 and 15 until 75 the end of the holder engages the rib 16. By virtue of the springs 17, the plate holder will be held firmly in clamped relation between the blocks 13 and 15 so that light may not enter with the consequent ruining of the 80 plate. The slide 22 covering the lowermost plate, in case a double plate holder is used, is then removed.

In order to provide means whereby the spring pressed bar 23 may be retracted out 85 of engagement with the plate to allow the plate to drop into the tray 10, I provide a rod 25 extending through one side of the block 13 and into the opening 14, and provided upon its inner end with an angular 90 portion 26 and upon its outer end with a knurled head 27. After the plate is inserted as previously described and the lower slide 22 removed, the operator grasps the head 27 and turns the rod 25 until the end 26 extends upwardly and engages the edge of the spring pressed bar 23. By then pulling upon the head 27, the bar 23 will be moved inwardly against the resistance of the spring, 95 whereupon the plate 24 will drop out of the 100 holder, through the opening 14 and onto the bottom of the tray 10. Developing solution is then poured into the funnel 12 whence it will flow through the tube 11 into the tray. The developer will then act upon the plate 105 in the usual manner, the operator preferably rocking the tray to prevent the collection of air bubbles upon the plate. After the developing solution has acted upon the plate the proper length of time, the tray is tilted so 110 that the solution will pass out through the tube 11. Water and the "fixing" solution

are then successively introduced and poured off in the same manner. After development is complete, the blocks 13 and 15 and the plate holder are removed, to permit access 5 to the tray.

From the foregoing description and a study of the drawing it will be apparent that I have thus provided a novel and simple device whereby photographic plates may be 10 transferred directly to a tray for development in broad daylight without danger of exposing the plate to light.

It will be readily understood that I reserve the right to make various changes in 15 the form, construction and arrangement of parts without departing from the spirit of the invention or limiting the scope of the subjoined claims.

Having thus described my invention, I 20 claim:

1. The combination with a photographic developing tray, of a frame disposed on the top of the tray, a clamping block disposed above the frame and adapted to coact with 25 said frame in holding a plate holder, a lug formed integral on the lower face of the clamping block and adapted to prevent longitudinal movement in one direction of the plate holder, and means for holding and 30 releasing the plate.

2. A photographic developing tray provided with a filling and discharge tube, a frame disposed on the top of the tray, a resiliently supported clamping block placed above the frame and adapted to coact with 35 said frame in holding a plate holder, a lug formed integral on the lower face of the clamping block and adapted to prevent longitudinal movement in one direction of the plate holder, and means for holding and 40 releasing the plates.

3. A photographic developing tray comprising a body member, a curved tube located at one end of the body member adapted to be used in emptying the contents of the 45 developing tray, a funnel disposed at the top of the tube adapted to facilitate easy filling of the tray, upwardly projecting ribs formed integral with the bottom for holding the plates to be developed in spaced relation thereto, and means for holding and 50 releasing said plates as and for the purpose set forth.

In testimony whereof, I affix my signature, in the presence of two witnesses.

FREDERICK D. RAMEAU.
